SWITCH CONTROL MEANS FOR VEHICLE LAMPS

Application filed April 24, 1931, Serial No. 532,582, and in Germany May 1, 1930.

The present invention relates to switch control means for vehicle lamps.

We have already constructed a switch box for the electric lighting of vehicles, in which a stop is provided between the switch positions for turning on the side lights and the head lights. This stop is adapted to prevent the switch from being accidentally rotated from the full head light position past the 10 dimming position into the side light or "out" position when changing from distant light to dimmed light on meeting an on-coming driver. In order to turn the switch past the stop the switch key must be displaced in its 15 longitudinal direction.

When switching from the side light position into the dimmed headlight position however the stop is not necessary, because this change is generally only made at the beginning of travel whereby the switch can be scarcely rotated too far by accident and also if this did happen there would be no serious results during travel. On that account the stop according to the present invention only 20 prevents rotation of the switch key in one direction, this switch key being displaceable in the longitudinal direction in known manner against a spring force.

In a known switch a press knob having an 25 inclined end surface has already been proposed as a stop for the switch lever. When turning the switch lever back, the press knob must be pressed down until the lever has been rotated at least partly over the press 30 knob. Two hands are necessary for this, one for pressing down the press knob and the other for turning back the switch lever.

In contradistinction to this, only one hand is needed to operate the switch according 35 to the present invention, by which hand the switch key can be pressed down and also rotated whilst the other hand can keep hold of the steering wheel.

Another known switch is locked against 40 rotation in every switch position and can be released by longitudinally displacing the switch key against spring force. As the switch has to be released before every turn of the switch it cannot be used however as 45 a dimming switch.

One form of construction of the invention is illustrated by way of example in the accompanying drawing in which:—

Figure 1 is an axial sectional view 55 through the switch box with the key inserted.

Figure 2 is a plan view of the switch box with the key removed.

Figure 3 is a view of the stop disc.

Figure 4 is an unwinding of the locking 60 disc and

Figure 5 is a view of the key.

A switch casing 4 has a neck 5 on the outside of the flange portion 6 of which are marked the four switch positions 0, 1, 2 and 3. A disc 7 having two locking teeth 8 which 65 are inclined on one side is welded to the inner side of the flange 6. The opening formed between the flange 6, the disc 7 and the key 10 is closed by a transversely slotted rotatable disc 9 through which the key 10 is adapted to be passed. The ward end of the key 10 is cut back at 19 so that two shoulder pieces are 70 formed.

A switch shaft 12 connected to a switch plate or roller 11 is provided with a longitudinal boring 13 for the body of the key 10, and a transverse slot 14 for the ward of the key 10. In addition the switch shaft 12 is not round at its upper end and a stop disc 15, 75 having two nose-pieces 16 adapted to co-operate with the locking teeth is non-rotatably but longitudinally displaceably mounted on the shaft 12 by means of a corresponding opening or aperture. The stop disc 15 is forced against the key locking disc 9 by a helical spring 17 abutting against the switch plate 11, the key lock disc 9 abutting against the disc 7. The shoulder pieces 19 of the key-ward rest on the disc 15 whilst the body of the key is held below in the bore 13 of the switch axle by two spring bolts 18 which permit the key 10 being pressed down. 80

In the plan shown, the key 10 together with the switch shaft 12 and the switch plate 11 can be suitably rotated to and fro between the positions 0 and 1. If the key 10 is rotated from 1 to 2 the two nosepieces 16 strike the inclined surfaces of the locking teeth 8 and slide along these, whereby the disc 16 is 85 displaced downwards against force of the 90 100

spring 17. In the position 2 the disc 15 is forced upwards again into its original position by the spring 17. The key 10 can now be suitably rotated to and fro between 2 and 3; the locking teeth 8 hereby form stops for the nosepieces 16 so that the key 10 cannot be accidentally rotated past 2 when rotating from 3 to 2. If the key 10 is to be turned back from 2 to 1, it is pressed downwards whereby it carries the disc 15 along with it against the force of the spring 17 by its two shoulders 19. Directly the key 10 is rotated by the same handle into the desired position 1 the spring 17 pushes the disc 15 back again into the normal upper position.

Only one hand and one handle is therefore required for turning the key from 2 to 1 whereby the manipulation of the switch is considerably facilitated.

20 The switch can be modified in suitable manner for example two nosepieces 16 can be mounted directly on the key 10. In this case the helical spring 17 can be disposed at the bottom in the bore 13.

25 We claim:

1. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, and means within said casing co-operating with said key to permit free rotation of said switch member in one direction to all the switch positions without longitudinal displacement of said key, but limiting rotation of said switch member in the other direction unless said key is first longitudinally displaced.

2. Switch control means for vehicle lamps comprising a casing, a switch member adapted to occupy at least three positions corresponding to different conditions of illumination of said lamps, a key adapted to be inserted in said casing to engage and operate said switch member, said member being freely rotatable in one direction to any of said switch positions without longitudinal displacement of said key, and means within said casing permitting rotation of said switch member in the other direction between only two of said switch positions without longitudinal displacement of said key.

3. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, and abutment means provided in said casing adapted to limit rotation of said key in one direction only but permitting free rotation in the other direction.

4. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, co-operating abutment members provided in said casing adapted to limit rotation of said key in one direction only but permitting free rotation in the other direction, and resilient means urging said abutment members together.

5. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, co-operating abutment members associated with said key, and resilient means urging said abutment members together, one of said abutment members having an inclined surface on one side so as to permit limited rotation of said key in one direction only but permitting free rotation in the other direction.

6. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, a fixed member within said casing having a projection extending therefrom, said projection having an inclined face, a member rotatable with said key and having a projection adapted to engage said projection on the fixed member, and resilient means pressing said last mentioned members into engagement with each other and adapted to permit said projection on the movable member to ride over the inclined surface of the projection on the fixed member to permit limited rotation of said key in one direction only but permitting free rotation in the other direction.

7. Switch control means for vehicle lamps comprising a casing, a rotatable switch member mounted in said casing and adapted to assume a plurality of positions corresponding to different conditions of illumination of said lamps, a key adapted to be inserted in said casing to engage and operate said switch member, and ratchet means associated with the key adapted to permit limited rotation of said key in one direction only, but permitting free rotation in the other direction.

8. Switch control means for vehicle lamps comprising a casing, a rotatable switch member mounted in said casing and adapted to assume a plurality of positions correspond-

ing to off, dim and full light conditions of said lamps, a key adapted to be inserted in said casing to engage and operate said switch member, and means within said casing co-
5 operating with said key to permit rotation of said switch member in one direction from off to full light positions without longitudinal displacement of said key but permitting rotation of said switch member in the other
10 direction only between dim and full light positions without longitudinal displacement of said key after initial rotation of said switch member from off to full light position.

In testimony whereof we have hereunto
15 affixed signatures.
